UNITED STATES PATENT OFFICE

BALTUS ROLFS AND PHILIP WEGE, OF WEST BEND, WISCONSIN, ASSIGNEES TO AMITY LEATHER PRODUCTS CO., OF WEST BEND, WISCONSIN

DESIGN FOR A BILL FOLD

Application filed October 17, 1930. Serial No. 37,300. Term of patent 3½ years.

To all whom it may concern:

Be it known that we, BALTUS ROLFS and PHILIP WEGE, citizens of the United States, residents of West Bend, in the county of Washington and State of Wisconsin, have invented a new, original, and ornamental Design for a Bill Fold, of which the following is a specification, reference being had to the accompanying drawing, forming part thereof.

The figure is a perspective view of the bill-fold showing our new design.

The characteristic feature of the design resides in the contour of the flaps and assemblage, the back of said billfold being of the same mottled design as the end portions on the inside thereof.

We claim:

The ornamental design for a billfold, as shown, and described.

BALTUS ROLFS.
PHILIP WEGE.
